8 Claims. (Cl. 90—59)

This invention relates to work supports and more particularly to an apparatus for supporting blade blanks in forming blades for turbines, compressors and the like.

It is frequently required in the formation of such hollow blades to provide an external nose radius less than the thickness of the sheet material which is folded about the leading edge. The folding may be accomplished if the nose is grooved internally before folding. The groove is proportioned so that its sides come close together when the opposite walls are brought together into blade relation by the folding operation. This proximity of the sides of the groove facilitates the filling of the groove by and bonding its sides together by solder. Since the walls are thin, for instance from 0.020 in. to 0.050 in., the cutting of the groove is difficult to accomplish.

It is a principal object of this invention to provide an apparatus for holding a blade blank in fixed position, free of distorting forces, during grooving of the inner nose wall.

Another object of this invention is to provide an apparatus having a removable mandrel for accurately locating the nose of a blade blank in operating position and having supporting structure for holding the blade in that position after the mandrel is removed and during grooving of the inner nose wall.

Referring to the drawings which disclose a preferred embodiment of the invention:

Fig. 1 shows in perspective a contoured blade blank which is to be folded about a small radius at the nose;

Fig. 2 is an end view of an enlarged fragment of the blank in Fig. 1;

Fig. 3 is a perspective view of a holding fixture, partly in section, wherein the mandrel is in position to move the nose of the blade blank into an operating position for cutting of the nose groove;

Fig. 4 shows the fixture means supported below a cutter for cutting the groove in the nose of the blank, the mandrel being removed;

Fig. 5 is an enlarged end view of a portion of the nose with the groove therein; and

Fig. 6 is an end view of a blade made from the grooved blank.

Referring now to the drawings, Fig. 1 shows a blade blank 10, such as would be held by the present apparatus, whose nose portion 11 and opposite side wall portions 12 have been formed to their selected contours. The walls define an open side and the leading edge L.E. at the nose of the blank. The nose is to be folded about the leading edge to provide an external radius of the nose equal to or less than the thickness of the wall at the nose. Fig. 2 is an enlarged view of a fragmentary section showing the relatively large nose curvature prior to the folding operation.

The apparatus is shown in Fig. 3 and comprises a base including the generally rectangular base plate 15 and an elongated back-up plate 16 which is attached to the upper surface of plate 15. Support means made up of upstanding walls 17 and opposed bearing elements 20

2

are also mounted on the upper surface of base plate 15. The bearing elements 20 are spaced apart to expose a portion of the upper surface of the back-up plate 16 along the length thereof and further, are shaped to conform to the shape of the outer surfaces of side walls 12, so that when the blade blank 10 is placed in the apparatus a substantial area of the walls 12 will be in contact with the elements 20 to reduce the possibility of distortion occurring during grooving. The elements 20 are preferably made of an elastomeric material such as Devcon, which is a plastic metal consisting of approximately 80% fine steel powders and 20% of an extremely strong plastic and is manufactured by the Chemical Development Corporation of Danvers, Mass. Such material is initially plastic and can be molded to the exact shape of the blade walls, and then permitted to harden into the final, desired shape.

A pair of hold-downs 25 having generally horizontal upper walls 26, vertical end walls 27 and vertical pressure transmitting walls 28, are connected to the upper edges of support walls 17 by means of the pins 30 which fit through appropriately formed holes in walls 26. Each pressure transmitting wall 28 extends downwardly into the interior of blade blank 10 and carries a shoe 31 which is constructed of the same material as bearing elements 20, the shoes having bearing surfaces 32 conforming to the shapes of the inner surfaces of side walls 12 opposite bearing elements 20.

When a blank is to be grooved, it is placed nose down in the apparatus so that the outer surface of its leading edge, L.E., contacts back-up plate 16 throughout the entire length of the nose. However, due to the fact that the shape of individual blade blanks may vary, it is possible that the leading edge of a blank will occasionally fail to make proper contact with the back-up plate. Therefore, a removable mandrel 35 has been provided which is insertable into the space between pressure transmitting walls 28 with its lower edge bearing on the inside surface of the nose wall. It can be forced down against the nose wall by releasable means comprising a bar 36 pivoted to a lug or ear 37 on one of the side walls 17 by bolt 38. The opposite end of the bar is slotted, as at 39, to fit around the threaded stud 40 protruding upwardly from ear 41 and a threaded handle 45 is mounted

on stud 40 for exerting a downward force against bar 36, this force being transmitted directly into and through mandrel 35 to force the leading edge against the surface of back-up plate 16. After the mandrel has been forced downwardly, the hold-downs 25 are tightened to urge the shoes 31 into engagement with the inner side wall portions of the blade blank. This is done by means of toggle clamps 50 bearing on the steps 51 of the hold-downs. Two such clamps are used at each end of the hold-downs.

Once the hold-downs have been tightened into position the handle 45 is backed away from bar 36 and the bar pivoted out of the way so that mandrel 35 can be removed. Since the hold-downs maintain the nose portion of the blade in proper position for grooving, the removal of the mandrel does not in any way affect the position of the blade. The entire apparatus can then be properly positioned beneath a cutting member, such as the rotating blade 52 shown in Fig. 4 and the inner nose wall grooved.

Fig. 5 shows the nose of the blade blank enlarged to portray clearly the groove 55 which has been cut in the nose wall. Fig. 6 shows the blade made by folding the blade blank at the leading edge about the desired small radius and after rounding off the trailing edge, the groove 55 having been filled with brazing material 56.

While the form of apparatus herein described constitutes a preferred embodiment of the invention, it is to

be understood that this invention is not limited to this precise form of apparatus and that changes may be made therein without departing from the scope of the invention which is defined in the appended claims.

What is claimed is:

1. In combination in an apparatus for supporting a hollow blade blank for internally grooving the nose wall thereof comprising a supporting fixture, a back-up plate mounted on said fixture, contoured bearing means fixed on said fixture for bearing against each of the contoured walls of a blade blank externally thereof, a removable mandrel positioned between said walls, releasable means for pressing said mandrel against the inner surface of said nose wall to bottom said nose against said plate in accurate relation thereto and throughout the length thereof, releasable hold-downs operable to press said walls against their respective bearing means with said nose wall supported on said back-up plate and accessible internally to a grooving tool while so supported.

2. An apparatus according to claim 1 wherein the bearing means comprises a plastic-like material casting.

3. An apparatus according to claim 1 wherein the hold-downs have shoes for pressing the walls of said blade blank against said bearing means, said shoes being made of a plastic like material.

4. In combination in an apparatus for supporting a hollow blade blank for internally grooving the nose wall thereof comprising a supporting fixture, a back-up plate mounted on said fixture, contoured bearing means fixed on said fixture for bearing against each of the contoured walls of a blade blank externally thereof, a removable mandrel positioned between said walls, releasable means for pressing said mandrel against the inner surface of said nose wall to bottom said nose against said plate in accurate relation thereto throughout the length thereof, releasable hold-downs operable to press said walls against their respective bearing means, and means retaining said hold-downs in operative position for securing said walls after said mandrel is removed from said nose wall.

5. An apparatus for supporting a blade blank having nose and side wall portions in fixed position for grooving of the inner nose wall, comprising a base, support means mounted on said base and including bearing elements for contact with the outer surfaces of said side wall portions, means including a removable mandrel for locating said nose portion in operating position with substantially the entire length of the outer surface of said nose against said base, hold down means spaced from each side of said removable mandrel and engageable with the inner surfaces of said side wall portions to hold said blade blank in position, and means engageable with said hold down means for maintaining said hold down means in contact with the inner surfaces of said side wall portions to hold said inner nose wall in position for grooving following removal of said mandrel.

6. An apparatus for supporting a blade blank having nose and contoured side wall portions in fixed position for grooving of the inner nose wall, comprising a base having a back-up plate mounted on the upper surface thereof, support means mounted on said base and including bearing elements conforming to the shapes of said side walls, said bearing elements being spaced apart and exposing a portion of the upper surface of said back-up plate along the length thereof, a removable mandrel

movable into an operating position to press said nose portion into contact along substantially the entire length of the leading edge with said back-up plate, hold down means spaced from each side of said removable mandrel

5 and engageable with the inner surface of said side walls to hold said blade blank in position after said mandrel is removed, and means engageable with said hold down means for maintaining said hold down means in contact with the inner surfaces of said side walls to hold said

10 inner nose wall in position for grooving.

7. An apparatus for supporting a blade blank having nose and side wall portions in fixed position for grooving of the inner nose wall, comprising a base having a back-up plate mounted on the upper surface thereof,

15 support means mounted on said base and including bearing elements conforming to the shapes of portions of the outer surfaces of said side walls, said bearing elements being spaced apart and exposing a portion of the upper surface of said back-up plate along the length thereof, a removable mandrel insertable into the space

20 between said bearing elements for contact with the inner nose wall of said blank, means including a pivotally mounted bar for exerting a downward force against said mandrel to force said blade nose portion into contact along substantially the entire length of its leading edge

25 with said back-up plate, hold down means connected to said support means, said hold means including pressure transmitting walls spaced from each side of said mandrel and extending into the nose portion of said blade blank,

30 shoes carried on said pressure transmitting walls and having bearing surfaces for contact with the inner surfaces of said side walls, and clamp means engageable with said hold down means for maintaining said shoes in contact with the inner surfaces of said side walls.

35 8. An apparatus for supporting a blade blank having nose and side wall portions in fixed position for grooving of the inner nose wall, comprising a base having a back-up plate mounted on the upper surface thereof, support means mounted on said base and including bearing ele-

40 ments conforming to the shapes of portions of the outer surfaces of said side walls, said bearing elements being spaced apart and exposing a portion of the upper surface of said back-up plate along the length thereof, a removable mandrel insertable into the space between

45 said bearing elements for contact with the inner nose wall of said blank, means including a pivotally mounted bar for exerting a downward force against said mandrel to force said blade nose portion into contact along substantially the entire length of its leading edge with said

50 back-up plate, hold down means connected to said support means, said hold means including pressure transmitting walls spaced from each side of said mandrel and extending into the nose portion of said blade blank, shoes carried on said pressure transmitting walls and having

55 bearing surfaces for contact with the inner surfaces of said side walls, and clamp means engageable with said hold down means for maintaining said shoes in contact with the inner surfaces of said side walls.
